BREAD TRAY

Howard L. Forman, New York, N.Y., assignor to Gorham Corporation, Providence, R. I.

Filed May 15, 1964, Ser. No. 79,993

Term of patent 14 years

(Cl. D44—10)

FIGURE 1 is a side elevational view of a bread tray or similar article showing my new design, and

The essential feature of the design resides in the particular configuration of the border ornamentation applied to a bread tray of conventional form.

I claim:

The ornamental design for a bread tray, as shown and described.
